[57] CLAIM

The ornamental design for a housing for base of telephone, as shown and described.

DESCRIPTION

FIG. 1 is a top-front perspective view of the housing for base of telephone with a broken line showing of a handset in a cradled position showing my new design;
FIG. 2 is a front elevational view of the housing for base of telephone of FIG. 1;

FIG. 3 is a right side elevational view of the housing for base of telephone of FIG. 1;

FIG. 4 is a left side elevational view of the housing for base of telephone of FIG. 1;

FIG. 5 is a rear elevational view of the housing for base of telephone of FIG. 1; and,

FIG. 6 is a top plan view of the housing for base of telephone of FIG. 1.

The bottom plan view of the housing for base of telephone of FIG. 1 is substantially flat and unornamented and forms no part of the claimed design.

The broken line showing of a handset in FIG. 1 is for environmental purposes only and forms no part of the claimed design.
